CLAIM

The ornamental design for a ball cap with ammunition holder, as shown and described.

DESCRIPTION

FIG. 1 is a perspective view of a ball cap with ammunition holder showing my new design, from a perspective to the right and a bit in front thereof;

FIG. 2 is a perspective view comparable to FIG. 1, except from a perspective to the left and rear thereof;

FIG. 3 is a left side elevational view thereof;

FIG. 4 is a right side elevational view thereof;

FIG. 5 is a top plan view thereof;

FIG. 6 is a front elevational view thereof;

FIG. 7 is a rear elevational view thereof; and,

FIG. 8 is a bottom plan view thereof.

The dot-dash-dot broken lines and the dash-dot broken lines represent environmental structures that form no part of the claimed design.
